United States Patent Office.

A. RICHMOND, OF BROOKLYN, AND SAMPSON G. RICHMOND, OF NORWICH, CONNECTICUT.

Design No. 3,347, dated January 19, 1869.

DESIGN FOR A COOK'S STOVE.

The Schedule referred to in these Letters Patent and making part of the same.

To all whom it may concern:

Be it known that we, A. RICHMOND, of Brooklyn, in the county of Windham, and SAMPSON G. RICHMOND, of Norwich, in the county of New London, all in the State of Connecticut, have originated and produced a new Design for Cooking-Stoves and Ranges, of which the following is a full and clear description, reference being had to the accompanying drawing, making part of this specification.

The invention relates to the formation of the edges and panels of the plates and doors of cooking-stoves or ranges, for the ornamentation thereof.

The drawings represent a stove embodying our design, the photograph showing the top, one side, and one end of the stove, and the detail sketch A, showing a cross-section of one edge of the top plate.

a denotes the top plate.

b, the front plate, and

c, the end plate.

e e, the oven and fire-pot doors.

f, the hearth, and

g, the moulding at the bottom of the range.

The edges of the top plate, and of the bottom plate and hearth, are formed with two smooth bevels, *h i*,

retreating from the flat surface of the plate, and the edges of the ash-pit door *k* are similarly formed with a double bevel, and the same feature may be carried out upon the doorse *e*, and upon the moulding *l*, which surrounds the bottom edge of the vertical plates of the stove.

Each door-panel is shown as containing a monogram, consisting of the letters CO upon the letters R. S., as seen in the detail B, and also in the detail at C, the monogram being cast upon the panels, and being in this instance the initial letters for "Richmond Stove Company."

The stationary plates of the stove may also have such a monogram, which is, of course, applicable to the plates and doors of any stove.

We claim the design for the edges of stove-plates, as shown in the drawings.

Also, the design of a monogram, cast upon the panels of the doors or stove-plates, as shown in the drawings.

A. RICHMOND.
S. G. RICHMOND.
